CHAIR

Aaron S. Goldberg, Philadelphia, Pa., assignor to
Bunting Glider Company, Philadelphia, Pa., a
corporation of Pennsylvania

Application August 24, 1953, Serial No. 26,570

Term of patent 14 years

(Cl. D15—1)

To all whom it may concern:

Be it known that I, Aaron S. Goldberg, a citizen of the United States, and a resident of Philadelphia, county of Philadelphia, State of Pennsylvania, have invented a new, original, and ornamental Design for a Chair, of which the following is a specification, reference being had to the accompanying drawing, forming a part thereof, wherein:

The figure is a perspective view of a chair showing my new design.

The characteristic features of the present design reside in the portions shown in full lines in the drawing.

I claim:

The ornamental design for a chair, substantially as shown and described.

AARON S. GOLDBERG.
